UNITED STATES PATENT OFFICE.

REINHOLD KRUMMING, OF MILWAUKEE, WISCONSIN.

TEMPORARY BINDER OR LOOSE-LEAF BOOK.

1,126,490.

Specification of Letters Patent. Patented Jan. 26, 1915.

Application filed January 21, 1914. Serial No. 613,573.

To all whom it may concern:

Be it known that I, REINHOLD KRUMMING, citizen of the United States, residing at Milwaukee, Wisconsin, have invented certain new and useful Improvements in Temporary Binders or Loose-Leaf Books, of which the following is a specification.

This invention relates to improvements in temporary binders or loose leaf books.

10 The main objects of this invention are: First, to provide a temporary binder or loose leaf book of the ring type, which is very convenient in use and one in which the parts are simple and economical to produce and 15 easily assembled. Second, to provide in a temporary binder of the class described, an improved rocking hook supporting plate structure. Third, to provide in a binder of the class described, an improved hook or 20 ring member structure.

Further objects, and objects relating to structural details, will definitely appear from the detailed description to follow.

I accomplish the objects of my invention 25 by the devices and means described in the following specification.

The invention is clearly defined and pointed out in the claims.

A structure which is a preferred embodiment of my invention is clearly illustrated 30 in the accompanying drawing, forming a part of this specification, in which:

Figure I is a detail inside view of a structure embodying the features of my invention, with the covers extended. Fig. II is an enlarged detail longitudinal section on a line corresponding to line 2-2 of Fig. I, with the cover closed and with sheets shown in conventional form. Fig. III is a rear view of the hook carrying plates or members removed from the back member. Fig. IV is a front perspective view of the back member with the hook carrying plates and hooks mounted thereon, the hooks being 40 shown in their open position. Fig. V is a detail section on a line corresponding to line 5-5 of Fig. I, the covers being omitted. Fig. VI is a sectional view corresponding to that of Fig. V, with the hooks in their open 45 position. Fig. VII is a detail rear view showing the mounting of the cover member upon the back member. Fig. VIII is a detail section on a line corresponding to line 8-8 of Fig. V, showing details of the hook 55 mounting or attachment to the hook carrying plates. Fig. IX is a similar section

showing slightly modified construction, the hook securing members being folded on the inner side of the hook carrying plates instead of riveted or upset.

In the drawing similar reference characters refer to similar parts throughout the several views, and the sectional views are taken looking in the direction of the little arrows at the ends of the section lines.

Referring to the drawings, the structure illustrated is provided with the flexible covers 1. The hook carrying members 2 and 3 are mounted on the rigid or non-yielding back plate or member 4. The covers are 70 preferably secured on the back plate 4 by the cover member 5, which is provided with loops 6 struck in to engage the longitudinally disposed tongues 7 projecting from the edges of the openings 8 in the back 75 member. See Figs. V, VI and VII. The back member 4 is curved in cross section and the cover member is curved to embrace it, as shown in the drawing.

The loops 6 are formed by slitting the 80 cover member transversely and striking in a strap-like loop portion, as shown, so that by placing the cover members over the back members with the loops 6 in the openings 8 and sliding the members longitudinally 85 relative to each other, the tongues and loops are engaged. This permits the assembling of the parts carried by the back member, and the covers upon the cover member, and assembling these after they are otherwise substantially complete.

The back member 4 is provided with inwardly turned flanges 9 at its edges, the outer edges of the hook carrying plates being disposed in the angles formed by these 95 flanges.

The hook carrying member 2 is provided with a rearwardly projecting flange 10 at its inner edge having longitudinal slots 11 therein, in which the tongues 12 on the plate 100 3 are disposed. These slots are arranged close to the plate 2. The tongues 12 are offset inwardly at 13 and rearwardly inclined to permit the plates to lie edge to edge. This provides a rocking connection for the inner 105 edges of the plates. The plates being supported in the angles of the flanges 9 are free to rock, the upward rocking movement being limited by the tongues 12 engaging the under side of the opposed plate, 110 see Fig. VI.

Springs 14, which are preferably bowed,

as clearly shown in Figs. V and VI, are arranged with their outer ends or edges in the angle formed by the plate 2, and the supporting back member. The inner ends 5 or edges of these springs engage the flange 10, the flange being provided with slots 15 for the tongues 16 of the springs. When the plates are rocked to the position shown in Fig. V or their closed position, these 10 springs are placed under tension, but owing to the fact that the plates are rocked past the center the springs cannot lift them. As soon as the plates are swung past the center 15 the springs act to swing them to and retain them in the open position, as shown in Fig. VI.

The plates are provided with finger pieces 24 at their ends for convenience in swinging or manipulating them.

20 The hooks or ring members 17 are preferably formed of sheet metal suitably curved to provide rounded surfaces and have integral base portions 18 with rivet extensions or tongues 19 at each side. These extensions are arranged through spaced rivet holes 20 in the plates and riveted therein, as shown in Fig. VIII.

In the modified construction in Fig. IX the rivet extensions 21 are longer than those 30 shown in Fig. VIII and are folded over on the inner side of the plates instead of being riveted thereon. This forms a very rigid and secure method of attaching the hooks or ring members to the plates, and one which 35 is very economical, in that the parts are economical to produce and quickly and easily assembled.

The plates are assembled with their tongues 12 engaging the slots 11, and the 40 tongues 16 of the springs engaging the slots 15 of the flanges 10, and the parts are then slipped longitudinally into the back member 4 and retained therein by turning up the ends 25 which are in the form of extensions on the ends of the back member. These ends 25 may, if desired, be soldered or brazed to the ends of the back member, but that is not ordinarily necessary. One 45 hook of each pair is provided with a V-shaped notch 22 and the other with an A-shaped tongue 23 fitting into the notch when the hooks are closed.

The notched and tongued hooks are arranged alternately so that a sheet can not 55 work from the hooks as might be possible where the tongued and notched hooks are all similarly disposed so that the openings between come in alinement.

I have illustrated and described my invention in detail in a very satisfactory embodiment. I have not attempted to illustrate or describe the various modifications which I contemplate, as I believe the disclosure made will enable those skilled in the art to 60 which my invention relates to embody or

adapt the same as conditions may require. I desire to be understood, however, as claiming my improvements specifically in the form illustrated as well as broadly within the scope of the appended claims.

Having thus described my invention, what I claim as new and desire to secure by Letters Patent is:

1. In a temporary binder, the combination 75 of a nonyielding back member having inwardly projecting flanges at its edges; hook carrying plates disposed with their outer edges within said flanges, one of said plates having a rearwardly projecting flange at its inner edge with slots therein close to the 80 body of the plate, the other plate having rearwardly inclined tongues at its inner edge disposed through said slots, said tongues being offset rearwardly at the edge of the plate whereby the plates are supported edge to edge for rocking movement, the tongues engaging the under side of the opposite plate to limit the upward throw of the plates; bowed springs arranged with their outer edge in the angle of said back 85 member and flanged plate, and with their inner edges engaging said flange and provided with tongues disposed through slots 90 therein; and hooks mounted on said plates in coacting pairs.

2. In a temporary binder, the combination 95 of a nonyielding back member having inwardly projecting flanges at its edges; hook carrying plates disposed with their outer edges within said flanges, one of said plates having a rearwardly projecting flange at its inner edge with openings therein, the other plate having tongues at its inner edge disposed through said openings whereby the plates are supported edge to edge for rocking movement; bowed springs arranged with their outer edge in the angle of said back 100 member and flanged plate, and with their inner edges engaging said flange and provided with tongues disposed through slots 105 therein; and hooks mounted on said plates in coacting pairs.

3. In a temporary binder, the combination 115 of a back member having inwardly projecting flanges at its edges; hook carrying plates disposed with their outer edges within said flanges, one of said plates having a rearwardly projecting flange at its inner edge with slots therein close to the body of the plate, the other plate having rearwardly inclined tongues at its inner edge disposed through said slots, said tongues being offset rearwardly at the edge of the plate whereby the plates are supported edge to edge for rocking movement, the tongues engaging the 120 under side of the opposite plate to limit the upward throw of the plates; and hooks mounted on said plates in coacting pairs.

4. In a temporary binder, the combination 125 of a back member having inwardly pro-

jecting flanges at its edges, hook carrying plates disposed with their outer edges within said flanges, one of said plates having a rearwardly projecting flange at its inner edge with openings therein, the other plate having tongues at its inner edge disposed through said openings whereby the plates are supported edge to edge for rocking movement; and hooks mounted on said plates in coacting pairs.

5. In a temporary binder, the combination of a nonyielding back member having inwardly projecting flanges at its edges; hook carrying plates disposed with their outer edges within said flanges and having a rocking connection at their inner edges; a spring arranged with its outer end in the angle of said back member and one of said plates, and with its inner end engaging a rearwardly projecting part on such plate, and provided with a tongue disposed through a slot therein; and hooks mounted on said plates in coacting pairs.

6. In a temporary binder, the combination of a nonyielding back member having inwardly projecting flanges at its edges; hook carrying plates disposed with their outer edges within said flanges and having a rocking connection at their inner edges; a spring arranged with its outer end in the angle of said back member and one of said plates, and with its inner end engaging a rearwardly projecting part on such plate; and hooks mounted on said plates in coacting pairs.

7. In a temporary binder, the combination of the hook carrying plates supported at their outer edges for rocking movement, one of said plates having a rearwardly projecting flange at its inner edge with slots therein close to the body of the plate, the other plate having rearwardly inclined tongues at its inner edge disposed through said slots, said tongues being offset rearwardly at the edge of the plate whereby the plates are supported edge to edge for rocking movement, the tongues engaging the under side of the opposite plate to limit the upward throw of the plates; a spring arranged with its inner end engaging said flange and provided with a tongue disposed through a slot therein, the outer end of said spring being supported so that the spring is placed under stress by the swinging of said plates past a central position; and hooks mounted on said plates in coacting pairs.

8. In a temporary binder, the combination of the hook carrying plates supported at their outer edges for rocking movement, one of said plates having a rearwardly projecting flange at its inner edge with slots therein, the other plate having tongues at its inner edge disposed through said slots whereby the plates are supported edge to edge for rocking movement; a spring ar-

ranged with its inner end engaging said flange and provided with a tongue disposed through a slot therein, the outer end of said spring being supported so that the spring is placed under stress by the swinging of said plates past a central position; and hooks mounted on said plates in coacting pairs.

9. In a temporary binder, the combination of the hook carrying plates supported at their outer edges for rocking movement, one of said plates having a rearwardly projecting flange at its inner edge with slots therein close to the body of the plate, the other plate having rearwardly inclined tongues at its inner edge disposed through said slots, said tongues being offset rearwardly at the edge of the plate whereby the plates are supported edge to edge for rocking movement, the tongues engaging the under side of the opposite plate to limit the upward throw of the plates; a spring arranged with its inner end engaging said flange, the outer end of said spring being supported so that the spring is placed under stress by the swinging of said plates past a central position; and hooks mounted on said plates in coacting pairs.

10. In a temporary binder, the combination of the hook carrying plates supported at their outer edges for rocking movement, one of said plates having a rearwardly projecting flange at its inner edge with slots therein, the other plate having tongues at its inner edge disposed through said slots whereby the plates are supported edge to edge for rocking movement; a spring arranged with its inner end engaging said flange, the outer end of said spring being supported so that the spring is placed under stress by the swinging of said plates past a central position; and hooks mounted on said plates in coacting pairs.

11. In a temporary binder, the combination of the hook carrying plates supported at their outer edges for rocking movement, one of said plates having a rearwardly projecting flange at its inner edge with slots therein close to the body of the plate, the other plate having rearwardly inclined tongues at its inner edge disposed through said slots, said tongues being offset rearwardly at the edge of the plate whereby the plates are supported edge to edge for rocking movement, the tongues engaging the under side of the opposite plate to limit the upward throw of the plates; and hooks mounted on said plates in coacting pairs.

12. In a temporary binder, the combination of the hook carrying plates supported at their outer edges for rocking movement, one of said plates having a rearwardly projecting flange at its inner edge with slots therein, the other plate having tongues at its inner edge disposed through said slots whereby the plates are supported edge to edge for

- rocking movement; and hooks mounted on said plates in coacting pairs.
13. In a temporary binder, the combination of the hook carrying plates supported at their outer edges for rocking movement, one of said plates being provided with a rearwardly projecting member, the inner edges of said plates having rocking connection; a spring supported to engage said rearwardly projecting member and disposed so that the spring is placed under stress by the swinging of said plates past a central position; and hooks mounted on said plates in coacting pairs.
14. In a temporary binder, the combination of the hook carrying plates supported at their outer edges for rocking movement, one of said plates being provided with a rearwardly projecting flange, the other having tongues arranged through openings in said flange; a spring arranged in engagement with said rearwardly projecting flange and disposed so that the spring is placed under stress by the swinging of said plates; and hooks mounted on said plates in coacting pairs, all coacting for the purpose specified.
15. In a temporary binder, the combination of a nonyielding back member, hook carrying plates having rocking engagement with said back member at their outer edges, one of said plates being provided with a rearwardly projecting member, the inner edges of said plates having rocking connection, a spring arranged below said plate having said inwardly projecting member with its inner edge in engagement therewith and disposed so that the spring is placed under stress by the swinging of said plates, and hooks mounted on said plates in coacting pairs, all coacting for the purpose specified.
16. In a temporary binder, the combination of a pair of rocking hook carrying members, and hooks arranged on said members in coacting pairs, there being a plurality of said pairs of hooks, one hook of each pair having a V-shaped notch in its end and the other a tongue adapted to fit said notch, the notched and tongued hooks being alternately disposed on said plates.
17. In a temporary binder, the combination of a pair of coacting hook carrying plates having hooks mounted on said plates in coacting pairs, there being a plurality of said pairs of hooks, one hook of each pair having a notch in its end, and the other a tongue closing into said notch when the hooks are closed, the notched and tongued hooks being alternately disposed on said plates.
18. In a temporary binder, the combination of a back member, hook carrying plates having rocking engagement with said back member, hooks carried by said plates, said back member being curved in cross section and having openings therein with tongues projecting into the openings thereof from one edge, a cover comprising a cover member curved to embrace said back member and having loops struck in therefrom adapted to slidably engage said tongues, whereby the cover member is secured to said back member.
19. In a temporary binder, the combination of a back member, said back member being curved in cross section and having openings therein with longitudinally disposed tongues projecting into the openings from one edge thereof, and a cover member curved to embrace said back member and having loops struck in therefrom adapted to slidably engage said tongues whereby the cover member is secured to said back member.
20. In a temporary binder, the combination of a back member, said back member having integral longitudinally disposed tongues thereon, and a cover member embracing said back member and having loops thereon adapted to slidably engage said tongues whereby the cover member is secured to said back member.
21. In a temporary binder, the combination of a hook carrying plate having spaced rivet holes therein, and a hook formed of sheet metal, said hook being longitudinally curved and curved in cross section and being provided with a base having integral rivet extensions at each side arranged through and riveted in said rivet holes in said plate, the longitudinal and transverse curvature of the hook being extended into the base between the said rivet extensions thereof.
22. In a temporary binder, the combination of a hook carrying plate having spaced rivet holes therein, and a curved hook formed of sheet metal provided with a base having integral extensions at each side arranged through and riveted in said rivet holes in said plate, the curvature of the hook being extended into the base between the said rivet extensions thereof.

In witness whereof, I have hereunto set my hand and seal in the presence of two witnesses.

REINHOLD KRUMMING. [L.S.]
